UNITED STATES PATENT OFFICE.

HARALD NIELSEN, OF STREATHAM, LONDON, ENGLAND.

FILLING MATERIAL FOR ABSORPTION, REACTION, MIXING, AND COOLING TOWERS.

1,307,635.

Specification of Letters Patent. Patented June 24, 1919.

Application filed December 29, 1916. Serial No. 139,695.

To all whom it may concern:

Be it known that I, HARALD NIELSEN, a subject of the King of Denmark, residing at 8 Madeira road, Streatham, London, England, have invented new and useful Improvements in Filling Material for Absorption, Reaction, Mixing, and Cooling Towers, of which the following is a specification.

In the chemical or other industries where absorption, reaction, mixing or cooling towers and the like are required, one of the most important factors which govern the size of tower, given the amount of liquor or gas to be dealt with per unit of time, is the packing or filling material with which the tower is packed, it being understood that the object of the filling material is to facilitate the contact between the liquor and gases.

It is clear that the larger the scrubbing or contact surface such a filling possesses and the greater the free space, that is to say, the smaller the percentage of the solid body of the material is in proportion to the volume taken up when the filling material is placed in position in a tower for instance, the smaller the tower can be in order to carry out a given amount of work.

A filling material or element which fulfills the above stated conditions is the one described in the complete specification of British Patent No. 26269, of 15th January, 1913. Practice has, however, shown that in order to facilitate the packing of large, especially high towers, this form of filling element must be considerably altered to suit the varying conditions. Besides the twisted winged element as therein described is liable to fracture owing to the outer edges being

free and unsupported. The improved form which is eminently suitable for the purpose is shown in the accompanying drawing and differs widely from that described in the above mentioned specification. Figure 1 shows a single element in perspective elevation. Fig. 2 a plan view of Fig. 1. Fig. 3 a method of stacking or assembling the elements. And Fig. 4 a partial sectional elevation of a modification in the construction of the acting surface.

Referring to the drawings it will be seen

that the single element consists of three helical or twisted surfaces *a* joined together at the edges, thereby forming a twisted hollow or tubular prismatic shaped body of refractory material. The top and bottom edges of the surfaces *a* of the filling element are made horizontal to secure the regular superimposition thereof.

These surfaces *a* may be smooth as shown in Figs. 1 to 3, or corrugated, as shown in Fig. 4, in transverse section and curved inwardly or outwardly, or they may be smooth or roughened according to requirements, and the element may be composed of three or more sides or surfaces.

In order to utilize these filling elements in a tower or the like, they can by the way of an example be placed together as illustrated in Fig. 3, thereby forming a series of cells or honeycomb-like structure, presenting the greatest possible surface combined with large free spaces *b*, *b'* for the liquor or gases between which a reaction, absorption or the like is to take place.

The special features of the filling material as above described are, that the curved surfaces tend to force the gas to assume a whirling motion which insures that new gas particles constantly come in contact with wetted surfaces, that no dust pockets are formed where grit or dirt can lodge, that it is completely self-draining and no capillary action can take place whereby the proper liquor distribution can be jeopardized, and further the filling material can be made very cheaply from any desired raw material required for special processes.

Claims:

1. A filling element for absorption, reaction, mixing and cooling towers comprising a three-sided hollow body of refractory material the acting surfaces of which are helically twisted while the top and bottom edges are made horizontal to secure the regular superimposition thereof.

2. A filling element for absorption, reaction, mixing and cooling towers comprising a plurality of surfaces of refractory material joined together at the edges and helically twisted to form a hollow prismatic body with their top and bottom edges made

horizontal to secure the regular superimposition thereof.

- 3: A filling material for absorption, reaction, mixing and cooling towers comprising
5 an aggregation of elements each with a plurality of surfaces joined together at the edges and helically twisted to form a hol-

low prismatic body, to constitute when superimposed a honeycomb-like structure, substantially as described.

10 In testimony whereof I have signed my name to this specification.

HARALD NIELSEN.
